(57) **CLAIM**

The ornamental design for a sink colander, as shown, and described.

DESCRIPTION

FIG. 1 is a perspective view of the sink colander;
FIG. 2 is a top side view of the sink colander;
FIG. 3 is a front view of the sink colander;
FIG. 4 is a right side view of the sink colander;
FIG. 5 is a left side view of the sink colander;
FIG. 6 is a rear view of the sink colander; and,
FIG. 7 is a perspective view of the sink colander in a use environment.

The broken lines are for illustrative purposes only and form no part of the claimed design.
